UNITED STATES PATENT OFFICE.

CLAUDE D. ENOCHS, OF LA CROSSE, WISCONSIN, ASSIGNOR TO THE VOTE-BERGER COMPANY, A CORPORATION OF WISCONSIN.

TELEPHONE-EXCHANGE APPARATUS.

No. 854,204.

Specification of Letters Patent.

Patented May 21, 1907.

Application filed April 24, 1905. Serial No. 257,052.

To all whom it may concern:

Be it known that I, CLAUDE D. ENOCHS, a citizen of the United States, residing at La Crosse, in the county of La Crosse and State of Wisconsin, have invented new and useful Telephone-Exchange Apparatus, of which the following is a specification.

My invention relates to improvements in telephone exchange apparatus of which the following is a full description, reference being had to the accompanying drawing forming part of this specification.

My invention concerns the operation of telephone circuits and more particularly although not exclusively the subscriber's line circuit and has for its object to provide means for equalizing the resistance of telephone circuits of different lengths and working under different conditions so that a lamp or other signal and electrical devices requiring a constant current may be operated directly without the interposition of relays.

Among the different features of my invention is embraced a sufficiently large steadyng resistance or ballast in circuit with the subscriber's line conductor containing a line lamp, jack and subscriber's set, whereby the resistance of the circuit when operated is steadied, the voltage across the line lamp regulated, and the efficiency of operation of the telephone apparatus increased.

By the use of my invention the line lamp is protected and the employment of an ordinary line relay now generally used with telephone systems is not necessary.

In no other branch of the electrical art is there shown to exist any such arrangement of multitudinous in-coming lines, each with its individual resistance varying so widely from others and all to be supplied from one and the same source of current. In no instance is there disclosed numerous separate circuits running from substantially a common current source to different distances and each including a lamp or lamps or other electrical device in series and ballasted so as to proportion the current to said lamp or device. Heretofore the more common arrangements have been to employ line relays to control local lamp circuits or to insert fixed resistances in series with the lamps so that lamps on different lines receive substantially the same current. It has also been usual to em-

ploy a source of current of sufficient potential to operate the line of a different resistance and rely upon artificial resistances in lines of lesser resistance to prevent too great a current on these latter lines. It has further been common practice to employ larger wires for long lines. It will however be noted that whatever means or device has been employed, it has been found necessary to separately test and classify so as to determine the necessary resistance to be added or the size of the wire to be used and since it has been too much labor and expense to have a different resistance or a different size of wire for each line, a certain grouping of lines of somewhere near the same resistance has been found necessary, and which has resulted only in a rough approximation of compensating resistance. None of these resistances vary. The added resistance is always the same and cannot increase its power to check any undue rise in current due to a sudden short circuit of the lines and it is new in the telephone art to employ a resistance that varies with the current. This invention makes it possible to insert into each line a simple, inexpensive device in no manner made especially for that line, which automatically accommodates itself to that line and which can be taken out and used on any other line of a different resistance and will automatically ballast this other line, and the device enables the line relays to be dispensed with.

In the accompanying drawing is shown a diagrammatic view of a simple telephone exchange system equipped with my invention, in which

A represents the line circuit. To this circuit is shown connected the subscriber's set or telephone B on one end and a line jack C, subsidiary signal or lamp D, battery E (in series) and impedance coil F at the other end of said circuit. Associated with the line jack are the answering and calling plugs or cords G and their co-operating parts (all of ordinary construction and familiar to those skilled in the art to which this invention relates). In the subscriber's circuit is placed what I have chosen to term a "ballast" H, directly in series with the line lamp. This ballast may be in the form of a conductor 2, made of iron wire or other suitable material,

inclosed in a sealed chamber 3, which may or may not contain an inert gas, as preferred. The ballast conductor decreases in conductivity as its temperature rises. In case the line has a high true resistance, the ballast receives a small amount of current and its resistance will be low; hence the line lamp will receive the larger proportion of the local drop inside the exchange. In case it has a low true resistance the ballast will receive more current, its resistance will very materially rise and the ballast will take up most of the local drop or voltage in the exchange, the drop across the line lamp being somewhat near what it was in case of a long subscriber's line. The steadyng resistance has a large positive temperature correction and this temperature correction is always immediately available. By using a sealed chamber as described and a fine iron wire conductor therein, the heat produced by the current passing through said conductor is not materially radiated and the corrective resistance and temperature of the ballast are thereby made extremely sensitive. It is obvious that by this circuit containing a ballast, as above employed, no line relay is necessary, and the drop of voltage in the line lamp is regulated with great nicety.

While I have shown only one form of ballast, it is obvious that other forms may be used without departing from the spirit of this invention to effect the results set forth, and I do not wish to be understood as confining myself to the exact materials, construction or arrangement of parts described.

Having described my invention, what I claim as new and desire to protect by Letters Patent, is:—

1. The combination with the conductors of a telephone line, a source of current and a signaling instrument in circuit with said line and a ballast in circuit with said signaling instrument to regulate its voltage.
2. In combination with the conductors of a telephone line, a source of current in circuit with said line, a signaling lamp, and a steadyng resistance in circuit with said lamp, for the purposes specified.
3. In combination with a telephone line circuit containing a signaling instrument at the central station, a ballast to steady the resistance of said circuit under variation of the electro motive force in said line.
4. In combination with a line circuit for conducting undulatory, pulsatory or intermittent electric currents, a signaling instrument connected with said line circuit, and a steadyng resistance in series with said signaling instrument, for the purposes specified.

5. In combination with a telephone line circuit having a jack, a signaling lamp, and a ballast, all connected in series therewith.

6. The combination in telephone apparatus of the subscriber's line circuit having a line jack, battery, signaling lamp, and a ballast placed in series with said lamp and the line contact of said jack to regulate the voltage across said lamp.

7. A telephone system having associated therewith line circuits of divers resistances, an electrical actuating device, a source of current and an automatic ballast resistance, for the purposes specified.

8. In a telephone system provided with line circuits, a sub-station telephone set for each circuit, a common source of current supply, and a ballast adapted to be associated with said circuits and to be directly affected by the current flowing therein to introduce an automatic compensating resistance proportionately to the amount of current flow, whereby current may be maintained constant in lines of various resistances.

9. In a telephone system, a central station, a subscriber's station, a line circuit interconnecting them, a source of current, means at the subscriber's station to determine the flow of current through the lines leading therefrom, a line signal and a ballast in series with the line circuit adapted to automatically vary proportionately to the current flow in said line.

10. In combination with the conductors of a telephone line, a source of current and a ballast adapted to be included in said line, for the purposes specified.

11. In combination with the conductors of a telephone line, a source of current, and a ballast composed of a conductor having a highly sensitive temperature correction.

12. A telephone system, comprising in combination with the subscriber's circuits, a source of current, and a ballast composed of an iron wire conductor having a highly sensitive temperature correction.

13. The combination with the conductors of a telephone line A, a line jack C, a signaling lamp D, a battery E and an impedance coil F, of a ballast H connected in series with said lamp and the line contact of said jack, for the purposes specified.

In testimony whereof I have signed my name to this specification in the presence of two subscribing witnesses.

CLAUDE D. ENOCHS.
